UNITED STATES PATENT OFFICE.

JOHN V. BLAIN, OF SPRING LAKE BEACH, AND OTTO M. MORRIS, OF SMITHBURG, NEW JERSEY.

PARIS-GREEN OR DRY-POWDER MACHINE.

1,122,847.

Specification of Letters Patent. Patented Dec. 29, 1914.

Application filed October 25, 1910. Serial No. 589,085.

To all whom it may concern:

Be it known that we, JOHN V. BLAIN and OTTO M. MORRIS, citizens of the United States, residing, respectively, at Spring Lake Beach and Smithburg, in the county of Monmouth and State of New Jersey, have invented certain new and useful Improvements in Paris-Green or Dry-Powder Machines, of which the following is a specification.

10 Our invention has relation to new and useful improvements in Paris green or dry powder machines and the main object thereof is to produce a device of this nature that will be efficient in operation, durable and 15 inexpensive to construct. This device is to be used when it is necessary to exterminate bugs or any kind of insects that are injurious to plants or any kind of plant-life that are liable to be infested thereby.

20 A further object of our device is to provide means to blow powder on a plurality of rows of plants at the same time and by the use of our invention the amount of powder used per acre may be regulated from, let us 25 say, for example, one to ten pounds.

A further object of our invention is to provide means to counteract the effect of the wind in the operation of spraying the powder throughout a field and also to regulate 30 the height of the sprayers by means of the same lever that is used in the regulation of the means for counteracting the effect of the wind. The shifting and hoisting means and the means for regulating the amount of 35 Paris green, or other powder employed, to be used, may be operated from the seat of the driver at will which is obviously a great advantage over other devices now in use.

With the above and other objects in view 40 our invention consists of the novel construction and arrangement of parts as are described in this specification, illustrated in the accompanying drawings forming a part thereof, and particularly pointed out in the 45 claims hereunto appended.

Referring to the drawings: Figure 1 is a side elevation of our invention as it would appear when ready for use. Fig. 2 is a top plan view of the same. Fig. 3 is a vertical, 50 transverse, sectional view taken on the line 3—3 of Fig. 2, looking in the direction of the arrow of parts above the bed. Fig. 4 is a bottom plan view of the invention. Fig. 5 is a detail elevation of the clutch and lever 55 therefor indicated in Fig. 4.

Referring more particularly to the drawings, our invention is described as follows:

The bed 1 is mounted upon wheels 2, by means of the bearings 3 and axle 4. A seat 5 is provided the construction of which is of any well known type.

Secured to the upper face of the bed 1 is a box or receptacle 5, which contains Paris green or other powder employed. Said receptacle 5 is provided with a spring cover 3 in its upper wall thereby providing means whereby powder may be placed into said receptacle. Formed adjacent to and in communication with said receptacle by means of openings 42' and 43, is a chamber 6 which contains a fan 7, said chamber provided with a plurality of openings 8 in its rear wall near the lower edge thereof. Protruding from each of said openings and extending rearward is a pipe 9, said pipes spreading as they extend rearward, each terminating in a distributing nozzle 10. The pipes are secured at their rear ends by means of staples 11, or any other suitable fastening means, to a shiftable member or crosspiece 12 slidably or adjustably held to the rear edge of a hinged tail board 40 to be hereinafter described, said shiftable member or crosspiece 12 being connected with the hinged tail board by means of pivoted pieces 13 which serve the purpose of horizontal hinges, whereby the shiftable member or cross piece 12 may be moved horizontally either to the right or left as desired. Said crosspiece may be shifted from the seat of the operator by means of a lever 14 pivoted thereto at 15, said lever being fulcrumed to the bed 1 at a point 16.

Rotatably mounted in the box or receptacle 5 upon a spindle 17, is an agitator 18, said spindle 17 being journaled in bearings 19, one of which is in one of the side walls of said receptacle, the other being at the upper end of the bracket 20. Said fan 7 is mounted upon a spindle 21, said spindle being journaled in bearings 22, one of which is in one of the side walls of the box 5, the other being at the upper end of the bracket 23.

Power is transmitted from the shaft 4 to a countershaft 24 by means of a sprocket chain 25 traveling upon the large sprocket wheel 26 and the small sprocket wheel 27, the proper tension being maintained by means of a tension holder 28. The shaft 24 is mounted for rotation in bearings in the 100 105 110

brackets 24'. From said countershaft 24 power is transmitted to the shaft 17 by means of a sprocket chain 29 traveling upon the sprocket wheels 30 and 31. Power is 5 also transmitted to the spindle 21 by means of a sprocket chain 32 or belt, if preferred, traveling upon the sprockets 33 and 34, said sprocket 33 being mounted upon a second countershaft 35, which shaft is rotated by 10 means of the chain 36 traveling upon the sprockets 37 and 38, said shaft 35 being journaled in bearings of the brackets 39.

The sprocket 37 is loosely held upon the shaft 24 but may be placed into engagement 15 therewith by means of a clutch 37', the clutch 37' comprising an enlargement 49 upon said shaft 24 which enlargement is provided with teeth 50 received by the notches 51 in the hub 52 of the sprocket 37, 20 when the sprocket 37 is in engagement with the shaft 24. By the use of a hand lever 53, having at its lower end a pair of prongs 54 engaging the neck 55 of the hub 54 the driver is enabled to throw the sprocket into 25 or out of engagement with said shaft 24 at will.

That the height of said distributing nozzles 10 may be varied the rear portion 40 of the bed 1 is separated from said bed and is 30 hingedly connected thereto by means of the hinges 41, said portion being adapted to be lowered or raised to whatever degree is desired by the manipulation of said lever 14.

In order to regulate the amount of powder 35 that passes through the opening 42 into the chamber 6 through the passage 43, we have provided a slide 44, which is adapted to be slid by the operation of a lever 45 fulcrumed to a bifurcated lug 46 secured to 40 the adjacent side wall of the box 5. Said lever is pivoted to the outer edge of the slide at 47. A scale 48 indicating the number of pounds of powder that will be used 45 per acre extends from the same side wall of said box as that to which the lever 45 is fulcrumed. When a certain amount of powder is desired to be used the handle is 50 shifted so that it coincides with the number on the scale indicating the number of pounds per acre that it is desired to utilize.

Heretofore in machines for distributing powdered material, such as Paris green, over growing plants, it has been proposed to feed such material into the path of an 55 air current from a fan or blower, but practical experience with such machines has demonstrated that a substantial portion of the powdered material is carried by the air current back into the receptacle, a certain 60 portion of such material being carried by the air current into and through the distributing pipes.

The foregoing and other objections are 65 overcome in a machine embodying the present invention by a new organization of

parts wherein the outlet 43 from the powder receptacle 5 is positioned in coaxial relation to the shaft of fan 7, whereby the rotation of said fan induces the inflow of powdered material into the "eye" of the fan, *i. e.* at the axis of rotation of said fan. As a result of this novel relation of the outlet to the fan, the powdered material is intimately mixed with the air, *i. e.* the fan acts to beat the material and to generate the air current, so that the powdered material is diffused through the air and is carried by it through distributing tubes 9 and nozzles 10. Manifestly, the air blown by the fan cannot flow into the receptacle 5, nor disturb the powdered material therein, but, on the contrary, the air is drawn with the powdered material through the axial opening 43 to the fan. It will be noted, further, that the distributing tubes 9, leading from the fan casing, are confined by keepers 11 loosely on a shifting member 12, the latter extending crosswise of the machine, at the rear thereof. This shifting member 12 is connected by hinges or pivoted pieces 13 to a tail board 40, the latter being in turn hinged at 41 to the wheeled frame 1. The member 12 is movable bodily in a horizontal direction crosswise of the machine, the hinges or pivoted pieces 13 permitting such movement relative to the tail board. Such horizontal movement of member 12 operates to simultaneously shift the pipes 9 and nozzles 10 to the right or left, as desired. Furthermore, the tail board 40 may be shifted in a vertical direction on the axis afforded by hinges 41, and thus the shifting member 12 with the nozzles may be raised or lowered as desired. The horizontal adjustment of the nozzles with member 12, and the vertical adjustment of tail board 40 with the shifting member and the nozzles, is effected by the single lever 14 having a loose connection 16 with the wheeled frame. It is apparent that the lever may be moved to the right or left to move member 12 and nozzles 10 horizontally to the left or right according to the direction in which the lever is shifted, such movement of the lever operating to simultaneously move the nozzles so that the powdered material may be properly blown upon the plants. Furthermore, the lever may be lifted to depress the tail board and the series of nozzles in order to direct the material upon plants of different heights.

The agitator 18 is positioned within the receptacle for operation directly in the throat leading to the inlet to the fan, so as to stir up and prevent clogging of the material. The quantity of material flowing from the receptacle into the fan is regulatable by the adjustment of slideable cut-off or valve 42, the operating lever 45 for which valve is positioned in coöperative relation

to a graduated member 48 so as to set the cut-off or valve to various positions according to the pound per acre it is desired to distribute.

5 By reference to Fig. 3 of the drawings it will be observed that hopper 5 is provided with a bottom 5^a, the latter being inclined from one side wall of the hopper toward the axially positioned inlet 43 to the casing 10 of the blower or fan. Said bottom 5^a terminates at one side of the axial inlet so as to produce a space or throat between the inclined bottom 5^a and the blower inlet, in which space flows the powdered material 15 from the hopper. This powdered material flows by gravity through the hopper and the inclined bottom of said hopper directs the powdered material into the throat or space next to the blower inlet, whereby the 20 material is fed by gravity to the throat and is drawn by the suction of the fan through an axial inlet. The regulating slide 42 is adapted to traverse the throat or space between the inclined bottom of the hopper 25 and the blower inlet, whereby the area of the throat or space is regulatable so as to control the quantity of powdered material flowing to the blower. This powdered material is liable to become clogged and owing 30 to the nature of the material it coagulates in lumps or charges, but, of course, the caked material must be broken up in the throat or hopper so that it will remain in a powdered condition and be free to flow 35 through the blower inlet. In order to break up the mass of material we provide the agitator, the same being in the form of a rotative member 18 on shaft 19. Said member is movable in a plane at a right angle to 40 the axis of the blower inlet and thus the agitator will operate in the throat or space so as to keep the material in a loosened condition. It is to be observed, accordingly, that the material is fed by gravity and is kept 45 in a loosened condition so as to insure the free flow of the material through the inlet to the blower or fan.

Having described our invention, what we claim as new, is:

50 1. In a machine for distributing powdered material, the combination with a wheeled frame, and a tailboard, of a horizontally slideable bar in coöperative relation to said tailboard, hinge members connecting

said bar to the tailboard for limiting said 55 bar to movement in a substantially rectilinear path with respect to said wheeled frame, distributing pipes attached directly to the horizontally slideable bar and shiftable simultaneously by the movement thereof, means for blowing air and powdered material through said pipes, and means connected to said bar for moving the latter and the pipes in a direction crosswise of the machine. 60 65

2. In a machine for distributing powdered material, the combination with a wheeled frame, of a tailboard movable up and down with respect to said wheeled frame, a slideable member connected to said tailboard for movement up and down therewith, said slideable member being movable horizontally on the tailboard independently of said up and down movement of said tailboard, a plurality of distributing devices 70 connected to and movable with said slideable member, and means operable at will for imparting movement to the slideable member and to the distributing devices so as to shift all the distributing devices simultaneously 75 and in a direction crosswise of the machine. 80

3. In a machine for distributing powdered material, the combination with a wheeled frame, of a tailboard hinged at the rear thereof for up and down movement 85 with respect thereto, a slideable member carried by the tailboard for up and down movement therewith, said slideable member being shiftable horizontally with respect to the tailboard and independently of the up 90 and down movement thereof, a lever connected to impart horizontal sliding movement to the slideable member in a direction crosswise of the machine, a blower, a series of distributing tubes connected with the 95 blower, and distributing nozzles attached to said tubes and carried on the slideable member so as to be movable simultaneously therewith and in a direction crosswise of the machine. 100

In testimony whereof we affix our signatures, in presence of two witnesses.

JOHN V. BLAIN.
OTTO M. MORRIS.
